TROUBLE LIGHT GUARD

Leonard Broder, 55 Cromwell St., Providence 7, R.I.

Filed Nov. 20, 1961, Ser. No. 67,620

Term of patent 14 years

(Cl. D48—16)

FIG. 1 is a perspective view of a trouble light guard, showing my new design;

FIG. 2 is a side elevational view thereof;

FIG. 3 is a rear elevational view thereof;

FIG. 4 is a top plan view thereof; and

FIG. 5 is a bottom plan view thereof.

The broken-line representation of a lamp, adjusting screw and lamp holder are for purposes of illustration only.

I claim:

The ornamental design for a trouble light guard substantially as shown and described.
